UNITED STATES PATENT OFFICE.

EDWIN H. BARKER, OF MOYLAN, PENNSYLVANIA, ASSIGNOR TO A. H. WIRZ, INC., OF CHESTER, PENNSYLVANIA, A CORPORATION OF PENNSYLVANIA.

REINFORCEMENT FOR SPRINKLER TOPS.

Application filed January 31, 1925. Serial No. 5,940.

My invention relates to pressed metal 55
sprinkler tops used primarily upon bottles
for dispensing liquids and having various
types of ultimate seal, usually closing by a
5 plug top or by a screw cap.

The main purpose of my invention is to
improve the seal of the flange element
(found in all of these several combinations)
10 by which the seal is effected against the
bottle thimble or the cork or against both.

A further purpose is to prevent rotation
of the flange element when the cap or top is
removed.

A further purpose is to provide a ring of
15 metal close to the skirt of the flange and
inside of it for the purpose of sealing to the
best advantage against the bottle thimble.

A further purpose is to provide an in-
terior ring of metal about the sprinkling
20 opening for the purpose of sealing against
a cork within the bottle.

A further purpose is to increase the
strength and reduce the weight of the flange
25 element by outwardly extending ribs con-
necting the inner and outer rings respec-
tively.

Further purposes will appear in the
specification and in the claims.

I prefer to illustrate my invention in one
30 general form only and have selected the
form with a view to illustrating to the best
advantage the principles involved.

Figure 1 is a central sectional elevation
35 showing my flange as adapted to use with a
plug top.

Figure 2 is a bottom plan view of the
flange of Figure 1.

Figure 3 is a perspective view of the
flange from below.

40 Figure 4 is a side elevation, largely in
central section of the flange mounted upon
a cork and with a plug top in place.

Figure 5 is a sectional view correspond-
45 ing generally to Figure 4 but showing also
a bottle to which the flange is applied.

Figure 6 is a sectional view correspond-
ing generally to Figure 5 but using a screw
cap and a washer in place of the bottle
cork.

50 Similar numerals indicate like parts in
the figures.

Describing in illustration and not in limita-
tion and referring to the drawings:—

The flange 5 is molded of soft metal and

is shown provided with the usual pouring
spout 6 and skirt 7. The bottle cork 8 is
shown as perforated at 9.

I have found it advantageous to form the
interior of the flange with downward fac-
ing rings or bosses 10 and 11, respectively 60
adjacent the perforation 9 and the outer
wall or skirt 7. These rings or bosses are
connected by preferably radial circumfer-
entially spaced stiffening ribs 12. The
flange is attached to the bottle 13 by spin- 65
ning the skirt in at 14 beneath the thimble
15 of the bottle.

The narrowing of the contact surfaces
upon the flange to annular bands very much
improves the efficiency of the seal secured 70
with the thimble 15 of the bottle and with
the cork 8, respectively. In addition I have
found that the ribs 12 not only stiffen the
flange, reducing the weight required for the
same service, but secure a very much better 75
hold upon the outer surface of the bottle
than would be secured by flat metal and
thus prevent rotation of the flange when
effort is made to twist out the plug or un-
screw the cap closure. 80

I thus secure the benefit of the stiffening
and strengthening ribs while increasing the
efficiency of the seal and reducing the
weight.

The aperture of the cap and cork in Fig- 85
ures 4 and 5 receive the sealing plug 16 of
a closure 17 of which one form is shown in
Wirz Patent No. 1,146,986, of July 20,
1915. The plug, of whatever type is in-
tended to enter the perforation 9 and seal 90
against the side walls of the perforation 9
is of smaller diameter of course than the
diameter of the opening in the pouring
spout 6.

In the form seen in Figure 6 the cork 8 95
is omitted and a washer 18 is used between
the ring 11 and the thimble of the bottle. A
washer 19 is also used between the cap 17
and the spout 20.

In this case there is additional sealing and 100
prevention of rotation due to the outer
ring along with considerable stiffening and
strengthening for the same weight though
the inner ring is not directly utilized.

It is my purpose to include herein all 105
variations and modifications in so far as they
fall within the reasonable spirit and scope of
my invention.

Having thus described my invention, what I claim as new and desire to secure by Letters Patent is:—

1. In a dispensing closure, a container for fluid having an outlet opening, an axially perforated cork fitting into the opening, a metal cap having a circumferential wall secured to the container about the outlet opening and having a perforation in registry with the cork perforation, an annular boss on the cap adjacent to and around the perforation on the side toward the cork, a second annular boss on the cap circumferentially adjacent the wall on the same side as the first and radial stiffening ribs joining the bosses. 5
2. In a dispensing closure, a container for fluid having an outlet opening, an axially perforated cork fitting into the opening, a metal cap having a circumferential wall secured to the container about the outlet opening, and having a perforation in registry with the cork perforation, an annular boss on the cap adjacent to and around the perforation, facing the top of the cork, a second annular boss circumferentially adjacent the wall and engaging the top of the container about the outlet and spaced radial stiffening ribs joining the bosses. 10
3. In a dispensing closure, a container for fluid having an outlet opening, an axially perforated cork fitting into the opening, a metal cap having a circumferential wall embracing the outlet and having a perforation in registry with the cork perforation, two spaced annular bosses on the cap, one sealing against the top of the cork, and the other engaging the container about the outlet and circumferentially spaced radial stiffening ribs joining the bosses. 15
4. In a dispensing closure, a container for fluid having an outlet opening and a rim free from threads and about the opening, a metal flange having a skirt adapted to engage with the rim to hold the flange to the bottle and a boss within the flange engaging the bottle about the opening. 20
5. In a dispensing closure, a container for fluid having an outlet opening and a rim about the opening, a metal flange having a skirt adapted to engage with the rim to hold the flange to the bottle and a boss and inwardly extending ribs engaging the end face of the bottle about the opening. 25
6. In a dispensing closure, a container for fluid having an outlet opening and a rim about the opening, a flange having a skirt engaging with the rim and having two spaced interior annular bosses and a pouring outlet, and a cork engaged by one of the bosses to seal against leakage of liquid between the skirt and the rim. 30
7. In a dispensing closure, a container for fluid having an outlet opening and a rim about the opening, a metal flange having a skirt for engagement about the rim, an interior boss in line with the rim and an outlet pouring spout in combination with a cork lying between the boss and the rim engaging the boss to seal against leakage between the rim and skirt. 35
8. In a dispensing bottle a closure cap adapted to fit about an outer bottle flange against the end of the bottle and beneath the flange and having an annulus to engage the end of the bottle, an apertured boss forming a pouring spout and stiffening ribs extending between the boss and annulus. 40
